US00D805892S

(12) **United States Design Patent** (10) **Patent No.:** **US D805,892 S**
Bard et al. (45) **Date of Patent:** **** Dec. 26, 2017**

(54) **PACKAGE**

- (71) Applicant: **Lutron Electronics Co., Inc.**,
Coopersburg, PA (US)
- (72) Inventors: **Benjamin F. Bard**, Zionsville, PA
(US); **David S. Bennett**, Bethlehem, PA
(US); **Jason C. Killo**, Emmaus, PA
(US)
- (73) Assignee: **Lutron Electronics Co., Inc.**,
Coopersburg, PA (US)
- (**) Term: **15 Years**
- (21) Appl. No.: **29/591,654**
- (22) Filed: **Jan. 23, 2017**

Related U.S. Application Data

- (63) Continuation of application No. 29/544,139, filed on Oct. 30, 2015, now Pat. No. Des. 780,569.
- (51) **LOC (10) Cl.** **09-03**
- (52) **U.S. Cl.** **D9/420**

Primary Examiner — Robert M. Spear*Assistant Examiner* — Darcey E Heflin(74) *Attorney, Agent, or Firm* — Saidman DesignLaw Group, LLC**CLAIM**

The ornamental design for a package, as shown and described.

DESCRIPTION

FIG. 1 is a front perspective view of a package showing our new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof; and,

FIG. 8 is another perspective view of the package shown in a partially closed configuration.

The broken lines illustrate structure or features which form no part of the claimed design.

1 Claim, 6 Drawing Sheets(56)
